HUMIDIFIER

Robert C. Barton, Pittsburgh, Pa.

Application September 28, 1931
Serial No. 565,659

2 Claims. (Cl. 98—109)

My present invention has reference to a new and novel construction of humidifiers for the register plates or frames for hot air heaters.

Among the objects of the invention is the provision of a humidifier for this purpose which comprises a frame to include side members having inwardly directed flanges against which the register plate or frame abuts and which secure the humidifier on the said frame, the side members being connected which provide the top of the body with a compartment for a water pan that is preferably filled with an absorbent material, there being simple but novel means for holding the pan in proper position, while a removable flanged closure covers the pan and the top of the frame and frictionally engages with the said frame in a manner to effectively sustain the closure thereon and likewise to permit of the removal of the closure or the swinging of the said closure on the frame when additional water is to be received in the pan.

To the attainment of the foregoing the invention consists in the improvement hereinafter described and definitely claimed.

25 In the drawing:

Figure 1 is a front elevation of one form of the improvement.

Figure 2 is a sectional view approximately on the line 2—2 of Figure 1.

30 Figure 3 is a front elevation of another form of the device.

Figure 4 is a sectional view approximately on the line 4—4 of Figure 3.

Figure 5 is a detail enlarged sectional view 35 approximately on the line 5—5 of Figure 4.

Figure 6 is a detail sectional view approximately on the line 6—6 of Figure 2.

The device is constructed of some suitable thin but strong metal. In the form of the invention as shown in Figures 1, 2 and 6 of the drawing the device is designed to be inserted between the wall and the hot air register plate or frame, the said plate may, however, be removed to arrange the humidifier in proper position and thereafter attached for contacting the depending and side portions of the humidifier and thus hold the same in a vertical position against the wall while in Figures 3, 4 and 5 the device is designed to be associated with a floor register. In each instance, it will be noted as the description progresses that the device not only affords a humidifier but a deflector for properly circulating the heated air that passes through the register.

55 Referring now to the drawing in detail and

Figures 1 and 2 in particular it will be noted that the device comprises a pair of spaced angle side members 1. The outer edges of the side members are cut at an inward curvature from adjacent the upper ends to the bottom thereof, 60 while the rear edges of the said side members are straight and these edges are formed with inwardly directed flanges 2. At a suitable distance above the lower ends of the sides, the said sides are connected and held in spaced relation 65 by an arched deflector plate 3. The outer edge of the deflector plate is rounded inwardly upon itself to afford the same with an open bead 4, and the sides have their outer edges provided with inwardly directed horizontal flanges 5 arranged below the bead. If desired, the bead may have its ends crimped over the flanges 5.

It will be noted that with this construction the combined humidifier and heat deflector is not provided with a back, except the lower end 75 of the deflector plate which is connected to the flanges 2, and as previously inferred the flanges directly below the said deflector plate 3 are designed to be passed between a vertically arranged hot air register plate and a wall, or the said 80 register plate may be removed and thereafter reattached to bind the flanges 2 against the box that is covered by the register plate.

Received in the open top of the frame or body provided by the sides and deflecting plate 3, 85 there is a pan. The pan 6 has an inclined bottom and has its side and rear edges flanged or rolled outwardly, as at 7, and has its shallow front formed with a bead 8 to be received between the lip 4 on the front and the flanges 5 on the sides. The flanges 7 rest on the flanges 5 and the rear rolled portion or flange of the pan is received over the rear ends of the said flanges 5, the rear vertical flanges 2 being slotted at their juncture with the horizontal flanges 5. The pan 90 is designed to receive therein a moisture absorbing and diffusing body 9, and this body is saturated with water, and additional water is supplied thereto at desired intervals. The cap or cover for the pan is indicated by the numeral 10 and is provided with apertures 10' disposed in the top thereof and arranged in alignment with the side edges of the top as indicated in Figure 6. It will be obvious that the apertures 10' allow 95 for the escape of moisture from the body 9. The cover has its sides and ends flanged, the side flanges indicated by the numeral 11 contacting with the outer faces of the sides 1 of the frame, the rear flange indicated by the numeral 12 being 100 designed to exert a frictional contact with 105 the outer face of the side member 1. The cover 110 has its outer edges flanged, the side flanges indicated by the numeral 13 contacting with the outer faces of the sides 1 of the frame, the rear flange indicated by the numeral 14 being

the rear flange of the pan, while the front flange 13 of the said cover is rounded and terminates in a round bead 14, the said bead designed to underline and to frictionally contact with the deflector plate 3 at the juncture of the bead 4 therewith. By this arrangement it will be noted that the cover is effectively sustained in position and that by gripping the lip 14 the said cover may be raised off or swung from its rear 10 on the frame so that a supply of water may be delivered to the pan. When in place the cover 10 affords a shelf, upon which books or other articles or ornaments may conveniently rest.

In the form of the invention as shown in Figures 3, 4 and 5 of the drawing, the sides 15 of the frame or body are connected together by a rear plate or back 16 and are held in spaced relation with respect to each other by an upwardly inclined deflector plate 17. The deflector plate 20 has formed on its upper end an inwardly directed open bead 18 is somewhat similar to the bead 4 of the form as shown in Figures 1, 2 and 6, and the space between the deflector plate and top of the frame or body affords ample room for a pan 19 which is provided with side flanges 20 that rest upon inturned flanges 21 formed on the upper edge of the sides 15 as clearly shown in Figure 5. The forward edge of the pan 19 is provided with a lip 22 that is outwardly directed and received between the deflector plate 17 and its bead 18 as shown in Figure 4, while the rear edge of the deflector plate is flanged or crimped as at 23, and the crimped portion is disposed in contact with the rear plate 16. The cover for 30 the form of the invention as shown in Figures 3, 4 and 5 is identical with that for the form shown in Figures 1, 2 and 6, therefore its structure will not be described again, and it will be noted that the parts of the cover for the form 40 as shown in Figures 3, 4 and 5 are indicated by the same reference numerals as the parts of the cover for the form shown in Figures 1, 2 and 6.

The edges of the sides 15 are cut at inward 45 curvatures, and the bottom of the sides 15 is formed with inwardly directed flanges 24 which together with an inturned flange 25 on the lower end of the back 16, are designed to be secured to a floor register and preferably between the body 50 of the register and its cover plate.

It is thought from the foregoing description that the advantages and novel features of my invention will be readily apparent.

I desire it to be understood that I may make changes in the construction and in the combination and arrangement of the several parts, provided that such changes fall within the scope of the appended claims.

Having described the invention, I claim:

1. A combined humidifier for hot air deflectors for the register plates of hot air furnaces, comprising a frame made up of two spaced side members having inwardly directed flanges to be contacted with and to be held in place by the register, an angle deflector plate connecting the sides and affording the top of the frame with an open compartment, a water pan having flanged edges received in the compartment and resting on the top of the frame, and a flanged apertured cover plate arranged over the top of the frame to cover the pan and frictionally secured in operative position by its flanges. 85

2. A combined humidifier, and air deflector for the register plate of hot air furnaces, including a frame comprising side members which have inwardly directed flanges over which the register plate is arranged and secured for sustaining the frame in vertical position, said side members having widened upper ends, a deflector plate arranged between and connected to the side members, said deflector plate at its outer end being formed with a rearwardly directed bead, the side members having on their upper ends inwardly directed flanges arranged below the bead, a water pan having an inclined bottom, and having its side and rear edges formed with flanges and its front edge formed with a lip to be received between the bead of said deflector plate and the upper flanges of the frame, a removable flanged apertured cover for the frame, the side flanges of the cover designed for frictional engagement with the sides of the frame and the front flange being arched downwardly and terminating in a bead which underlies and frictionally contacts with the deflector plate to cooperate with the side flanges of the cover to secure the latter in operative position. 100
